WILLIAM PARKIN, OF TAUNTON, MASSACHUSETTS, ASSIGNOR TO
REED AND BARTON, OF SAME PLACE.

Design No. 3,439, dated March 30, 1869.

DESIGN FOR A TABLE-CASTER STAND.

The Schedule referred to in these Letters Patent and making part of the same.

To all persons to whom these presents may come:

Be it known that I, WILLIAM PARKIN, of Taunton, in the county of Bristol, and State of Massachusetts, have invented or produced a "New Ornamental Design for a Table-Caster Stand;" and I do hereby declare the same to be fully described in the following specification, and represented in the accompanying drawings, of which—

Figure 1 is a side elevation; and

Figure 2, an end view of it.

The base, A, is a rectangular plate, having a series of bowls, or cups, B B, &c., projecting down from and opening at top through it, or made with openings to receive bottles, salt-cups, or other articles.

At each corner is an ornamental bracketed leg, C, surmounted by a bust, a.

Extending up from the base, A, are two standards, D D, surmounted by a bar, E, on the middle of which is an eagle, F, with wings spread.

The posts are flanked and supported by two knights, or men in armor, H H, each carrying a shield, b, and a staff, c.

Tassels, G G, are suspended from the bar E, near its opposite ends.

I claim the design, substantially as described and represented.

WILLIAM PARKIN.
